DESIGN FOR A COMBINED LAMP AND SMOKER'S STAND

Jacob Forbes, Philadelphia, Pa.

Application January 21, 1937, Serial No. 67,211

Term of patent 3½ years

To all whom it may concern:

Be it known that I, Jacob Forbes, a citizen of the United States, residing at Philadelphia, in the county of Philadelphia and State of Pennsylvania, have invented a new, original, and ornamental Design for Combined Lamp and Smoker's Stand, of which the following is a specification reference being had to the accompanying drawing forming part thereof.

I claim:

The ornamental design for a combined lamp and smoker's stand, as shown.

JACOB FORBES.
